Primary Examiner — Christian P. McLean*Assistant Examiner* — Katherine E Morris(74) Attorney, Agent, or Firm — Michael Bartholomew(57) CLAIM

The ornamental design for a spray bottle, as shown and described.

DESCRIPTION

FIG. 1 is a top perspective view of the spray bottle, showing our new design;

FIG. 2 is a bottom perspective view thereof;

FIG. 3 is the right side elevational view thereof;

FIG. 4 is the left side elevational view thereof;

FIG. 5 is the front elevational view thereof;

FIG. 6 is the rear elevational view thereof;

FIG. 7 is the top plan view thereof; and,

FIG. 8 is a bottom plan view thereof.

The broken lines in the drawings illustrate the portions of the spray bottle, which form no part of the claimed design.

1 Claim, 8 Drawing Sheets(56)
